UNITED STATES PATENT OFFICE.

ELLSWORTH A. HAWTHORNE, OF BRIDGEPORT, CONNECTICUT.

DESIGN FOR A LAMP-HOOD.

44,308.

Specification for Design.

Patented July 8, 1913.

Application filed March 22, 1913. Serial No. 756,924. Term of patent 14 years.

To all whom it may concern:

Be it known that I, ELLSWORTH A. HAWTHORNE, a citizen of the United States, and a resident of Bridgeport, county of Fairfield, State of Connecticut, (whose post-office address is 35 Spruce street, Bridgeport, Connecticut,) have invented a new, original and ornamental Design for a Lamp-Hood, of which the following description, in connection with the accompanying drawings, is a specification.

In the drawings: Figure 1 is a side view of a lamp equipped with a hood having the

design of my invention, Fig. 2 is a side elevation of the hood shown on a larger scale; and Fig. 3 is a front elevation of the same.

What I claim is—

The ornamental design for a lamp hood, as shown.

In testimony whereof, I have signed my name to this specification, in the presence of two subscribing witnesses.

ELLSWORTH A. HAWTHORNE.
